UNITED STATES PATENT OFFICE.

MALACHI A. CARRIKER, OF NEBRASKA CITY, NEBRASKA.

SPECULUM.

SPECIFICATION forming part of Letters Patent No. 552,415, dated December 31, 1895.

Application filed November 2, 1894. Serial No. 527,775. (No model.)

To all whom it may concern:

Be it known that I, MALACHI A. CARRIKER, a citizen of the United States, residing in Nebraska City, in the county of Otoe and State of Nebraska, have invented a new and useful Surgical Instrument; and I do declare that the following is a full, clear, and distinct description of my invention, which will enable others skilled in the art to which it applies and all persons for whom it is intended to successfully use the same.

The object of my invention is to assist physicians in the successful treatment of catarrhal and ulcerated conditions of the endometrium, cervical canal, os uteri, and malpositions of the uterus and enable patients to more successfully treat said conditions themselves.

The nature of my invention is such that patients can use it as successfully as physicians for the purposes herein set forth; and my invention consists in the construction and arrangement of an applicator, as will be hereinafter more fully set forth.

Figure 1 shows the ring-handle, piston-rod, piston, and cap. Fig. 2 represents the sponge, cotton, woolen, or any other elastic pledge, the cord for removing the pledge from the vagina, and point of cord attachment to pledge. Fig. 3 represents said pledge in position on bell-mouth, with point of attachment to pledge upward and at center of it, where and as it must be when passing said pledge through the applicator and the cord passed through bell-mouth, cylinder, hollow truncated cone and drawn outside of applicator through the vertex of a slot of said hollow truncated cone. Fig. 4 represents my invention with part of a section of the hollow truncated cone removed to show piston, pledge, cord attachment to pledge in position for passing applicator through vagina to os uteri. Fig. 5 represents the elastic blades of said hollow truncated cone extended to their required limit, the piston in distal end of said hollow truncated cone, and said pledge as they should appear at os uteri, with said cord drawn backward outside of applicator.

The ring-handle N is constructed so that it will receive either finger when in use. Piston-rod O is of such length that piston C will pass beyond distal end T of hollow truncated

cone H and always release pledge D when medicated tablet E is deposited at os uteri, and the diameter of piston C is exactly that 55 of the inside of cylinder B, so that said pledge D cannot be caught between piston C and cylinder B nor between distal ends T of elastic blades J of hollow truncated cone H and piston C when passing said pledge D 60 through said applicator. Cap P is constructed without neck or head to shorten length of said applicator. Rim of cap P is narrow, so that two turns will adjust it to bell-mouth I, while threads of cap P are large to give 65 strength to screw U. Bell-mouth I is constructed so that said pledge D can be easily passed through it into cylinder B, which is continuous into a hollow truncated cone H, which consists of concavo-convex elastic 70 blades J, between which are slots K, the sides of which converge from their bases S to their vertices T.

The hollow truncated cone H is constructed so that the elastic blades J which form it approximate at their vertices T, and the hollow truncated cone H is thus constructed so that it can be introduced into and passed through the vaginal canal with the least possible resistance; and the blades J of said hollow 80 truncated cone H are made to be elastic, so that they can be extended parallel with the sides of cylinder B, and thus permit piston C to drive pledge D and medicated tablet E through the hollow truncated cone H, Fig. 5, 85 and when the piston C has been withdrawn the elastic blades J return to their natural positions, re-forming said hollow truncated cone H, Fig. 4, while the object of the said elastic blades J approximating at their vertices T, Figs. 3 and 4, is so that they will not catch and pinch the vaginal mucous membrane between them when the applicator is passing through the vagina to os uteri. The use of the cord F is to remove said pledge D 90 from os uteri, while the object of the elastic pledge D is to retain the medicated tablet E against os uteri to absorb catarrhal discharges or for a uterine pessary.

To use my speculum, take pledge D and 100 pass the free end of cord F down through bell-mouth I, Fig. 3, cylinder B, hollow truncated cone H. Then place said pledge D on bell-mouth I, so that cord F, attached to said

pledget D, will be on the upper side and in center of said pledget D at point G and pass outward over top and downward over edge of said pledget D, so that Q will be exactly on a line with any slot K. Then with fingers and thumb carefully and evenly press said pledget D down through said bell-mouth I, cylinder B, and into upper part of said hollow truncated cone II just far enough so that the elastic blades J of said hollow truncated cone II do not separate at their vertices T, Fig. 4. Then make traction on cord F at point R until slack is taken out. Then bring said cord F outside of said truncated cone II through the vertex T of any slot K that is exactly on a line with Q, so that cord F takes the direction M. Next place piston C on said pledget D, adjust cap P, Fig. 4. Then put medicated tablet E through any slot K flat against the distal side of said pledget D, Fig. 4. Then lubricate said truncated cone II and pass the applicator, Fig. 4, through the vaginal canal to os uteri, drive piston C to distal end T of said hollow truncated cone II, which will place medicated tablet E in position at os uteri with pledget D against it, Fig. 5. When the medicated tablet and pledget D have been placed in position at the os uteri take hold of cap P, Fig. 5, and draw the instrument backward one inch, the piston C backward two inches, then withdraw the speculum from vaginal canal.

Having thus fully described my invention, what I claim as new and original, and desire to secure by Letters Patent, is—

1. A surgical speculum in substantially cone shape, having its walls for a portion of its length longitudinally divided to form flexible concavo-convex separate blades or leaves normally approximating at their apices.

2. A speculum, consisting of the hollow cylinder B, having a threaded bell-shaped mouth, and concavo-convex elastic blades J, approximating at their vertices T, substantially as shown and described and for the 45 purposes set forth.

3. A speculum, consisting of the hollow cylinder, provided with a bell-shaped mouth, and concavo-convex elastic blades, approximating at their vertices, substantially as 50 shown and described and for the purposes set forth.

4. A speculum, consisting of the hollow cylinder B; having a threaded bell-shaped mouth, and concavo-convex elastic blades J, 55 approximating at their vertices T; perforated and threaded cap P, screwing onto the mouth of the cylinder; piston rod O, working through the perforation of the cap P, and provided with ring handle N, and concavo-convex piston C, substantially as shown and described and for the purposes set forth.

5. A speculum, consisting of the hollow cylinder, having a bell-shaped mouth and concavo-convex elastic blades, approximating at 65 their vertices; perforated cap fitting over the mouth of said cylinder; a piston rod working through the perforation in said cap, and provided with a suitable handle and piston, substantially as shown and described and for the 70 purposes set forth.

In testimony that I claim the foregoing I have hereunto affixed my signature, this 9th day of October, 1894, in the presence of two witnesses.

M. A. CARRIKER.
